(57) **CLAIM**

The ornamental design for the footwear sole, as shown and described.

DESCRIPTION

FIG. 1 is a front elevational view of a footwear sole showing the new design.

FIG. 2 is a rear elevational view thereof.

FIG. 3 is a left side elevational view thereof.

FIG. 4 is a right side elevational view thereof.

FIG. 5 is a bottom plan view thereof.

FIG. 6 is a top plan view thereof; and,

FIG. 7 is a bottom perspective view thereof.

The broken lines depict portions of the footwear sole that form no part of the claimed design.

1 Claim, 5 Drawing Sheets
